UNITED STATES PATENT OFFICE.

ROY J. COOK, OF CHICAGO, ILLINOIS, ASSIGNOR TO GEORGE C. MURRAY, OF CHICAGO, ILLINOIS.

FRictional DRAFT GEAR.

Application filed December 30, 1918, Serial No. 268,943. Renewed August 4, 1922. Serial No. 579,768.

To all whom it may concern:

Be it known that I, Roy J. Cook, a citizen of the United States, residing at Chicago, in the county of Cook and State of Illinois, have invented certain new and useful Improvements in Frictional Draft Gears, of which the following is a specification.

This invention relates to draft rigging for railway cars and the like, and its purpose is to provide an improved form of friction draft gear. The principal object of the invention is to provide a friction draft gear comprising an improved construction and arrangement of the frictional coating elements. A further object is to improve the efficiency of the draft gear by providing an increased number and an improved arrangement of the frictional surfaces. Other objects relate to various features of construction and arrangement which will be set forth more clearly hereinafter. Other objects and advantages of the invention will appear from the following specification taken in connection with the accompanying drawings in which two embodiments of my improved draft gear are illustrated.

In the drawings—

Figure 1 shows a top plan view of the draft gear with a portion thereof shown in horizontal section on the line 1—1 of Fig. 2;

Fig. 2 shows a vertical section through the draft gear on the line 2—2 of Fig. 1;

Fig. 3 shows a perspective view of one of the casings adapted to coat with and support the friction blocks;

Fig. 4 shows a side elevation of the draft rigging with the lower part thereof illustrated in vertical section on the line 4—4 of Fig. 2;

Fig. 5 shows a perspective view of a combined spring cap and friction block;

Fig. 6 shows a perspective view of the other side of the member illustrated in Fig. 5;

Fig. 7 shows a perspective view of one of the intermediate friction blocks adapted to coat with the blocks shown in Figs. 5 and 6, and

Fig. 8 shows a top plan view similar to Fig. 1 of a modified form of the invention in which the intermediate friction blocks are divided by a transverse plate in order to increase the number of frictional contacting surfaces.

In the drawings, my improved draft gear is shown mounted between draft sills 10 of channel form which have the usual draft lugs 11 secured thereto by rivets 12. The draft gear mounted between the sills 10 is supported by the carrier bars 13 which extend between the draft sills and are secured to the lower flanges thereof by means of bolts or rivets 14. The draw-bar yoke 15 of usual form has the forward ends of its upper and lower arms secured by rivets 16 to the butt 17^a of the draw-bar 17, and the lower arm of the yoke is adapted to enter the depressions 13^a formed in the carrier bars 13.

The friction draft gear mounted within the yoke 15 comprises two casings 18 of the form illustrated particularly in Fig. 3. Each casing 18 comprises upper and lower walls or plates 19 and 20, respectively, connected at their rear ends by the rear wall 21 which is formed integrally therewith. The upper and lower plates 19 and 20 are united adjacent their forward edges by means of the integral inclined diverging plates or flanges 22 which are united to the rear wall 21 by the integral webs 23. The rear wall 21 is provided with a dowel pin or lug 21^a to engage the spring of the draft gear, and the upper and lower walls 19 and 20 are further provided with apertures 19^a and 20^a to permit access to the parts of the gear within the casing.

Two of these casings 18 are mounted within the yoke 15 and rest upon the carrier bars 13, as shown in Fig. 2. The casings 18 are mounted in the yoke with the rear wall 21 of one casing abutting against the rear face of the coupler butt 17^a, and with the rear wall 21 of the other casing engaging the rear wall of the yoke 15. Mounted between the casings 18 are two friction blocks 25 of the form illustrated particularly in Figs. 1 and 7. Each block comprises two hollow heads 25^a which are of triangular cross-section and which are connected by the intermediate web or plate 25^b. Each of the members 25^a comprises two outwardly diverging contacting surfaces 25^c. The surfaces 25^c at the outer end of each block are adapted to coat with and slide upon the outer similarly inclined surfaces of the walls 22 formed on the casings 18. The surfaces 25^c on the inner heads 25^a of the blocks 25 are adapted to contact with and slide upon

the surfaces 26^c which are formed on the innermost wedging blocks 26. Each block 26 comprises two diverging plates 26^a upon which the surfaces 26^c are formed, and these 5 plates are united by the end plates or flanges 26^b. Each block 26 is further provided with a rear wall or plate 26^d, and the block is reinforced by webs 26^e extending between the wall 26^d and the flanges 26^a. A dowel 10 pin or lug 26^f is formed on the rear face of each wall 26^d for engagement with one end of one of the springs hereinafter described. The inner head 25^a of each block 25 is cut away at its upper and lower ends, as shown 15 at 25^d, so that the end faces of these heads slide upon the end walls 26^b of the inner blocks 26. The lugs 25^e formed by cutting away the ends of the inner members 25^a extend between the oppositely disposed edges 20 of the end walls 26^b of the blocks 26 and serve to effect an automatic positioning of the elements when the yoke is in its normal position.

Two concentrically located coil springs 28 25 and 29 are mounted on each of the rear walls 21 of the casings 18 and the oppositely disposed walls 26^d of the blocks 26, these springs being located within the casings 18 and being retained in position by the dowel 30 pins 21^a and 26^f heretofore described. These springs normally force the blocks 26 toward each other and thus maintain the elements of the draft mechanism in the normal position illustrated in Fig. 1.

35 When the draw-bar is moved forwardly, the forward casing 18 remains stationary against the forward draft lugs 11, and the rear casing 18 is moved forwardly by the yoke 15. The forward movement of the rear 40 casing 18 operates to move the friction blocks 25 in an outward and forward direction due to the coaction of the inclined walls 22 with the inclined surfaces of the outer heads 25^a of the blocks 25. This causes the inner heads 25^a of the blocks 25 to slide outwardly on the inclined surfaces 26^c of the blocks 26, whereupon the blocks 26 are moved away from each other toward the opposite ends of the draft rigging, thus 45 compressing the springs 28 and 29 between the blocks 26 and the end walls 21 of the casings. When the draw bar is moved rearwardly, the forward casing slides in a rearward direction, while the rear casing 18 remains 50 stationary against the rear draft lugs 11, whereupon the springs 28 and 29 are again compressed by movement of the friction blocks somewhat similar to that just described, as will be apparent from the foregoing 55 description.

In Figs. 8 of the drawings, I have illustrated a modified form of the invention above described. This modification is similar to the first form except that an additional member has been added at the central 60

part of the draft gear in order to increase the number of frictional coacting surfaces. In this embodiment of the invention two casings 35 are provided within the yoke 36, these casings being similar to the casing 18 70 employed in connection with the first form of the invention, being provided with inwardly converging flanges 37. The intermediate friction blocks corresponding to the blocks 25, previously described, are divided in this form of the invention, there being two blocks 38 divided by a transverse plate 39. The two blocks 38 at each side of the draft gear form together a structure similar to the single block previously described, and these blocks coact with the central V-shaped friction blocks 40 which engage the coil springs 41 and 42 extending between the central blocks and the end walls 80 of the casings. The transverse plate 39 is 85 provided with oppositely directed central lugs 44 which engage apertures in the central parts of the blocks 38, and thus guide and support the plate 39 as the blocks 38 slide thereon. It will be seen that as the draft gear is compressed, the gear will move outwardly between the flanges 37 and will thus slide on the plate 39 in addition to sliding on the inclined surfaces of the block 40, thus increasing the frictional resistance 95 which is opposed to the movement of the draft gear.

While I have shown and described two embodiments of the invention for purposes of illustration, it will be understood that the 100 apparatus may be constructed in various different forms without departing from the scope of the appended claims.

I claim:

1. The combination in a draft gear, of a 105 yoke, a pair of casings mounted within said yoke, each of said casings having inclined flanges converging toward the central part of the draft gear and toward the opposite casing, draft lugs engaging said casings, friction blocks mounted between said casings and coacting with the inclined flanges thereof, and compression devices engaging said casings and said friction blocks.

2. The combination in a draft gear, of a 110 pair of casings each having two inclined flanges converging toward the central part of the draft gear, a pair of friction blocks each having converging surfaces coacting with one flange of each of said casings and having other diverging inclined surfaces directed inwardly therefrom, central friction blocks having inclined surfaces coacting with said last-named surfaces of said first-named friction blocks, and compression devices 115 engaging said central friction blocks.

3. The combination in a draft gear, of a 120 pair of casings having upper and lower walls united by converging flanges directed toward the central part of the draft gear, 125

- intermediate friction blocks having inclined surfaces coacting with said flanges and having other diverging surfaces directed inwardly from said flanges, central friction blocks having diverging surfaces coacting with the last-mentioned surfaces on said intermediate friction blocks, and springs mounted within said casings and engaging said central friction blocks.
4. The combination in a draft gear, of oppositely disposed casings having upper and lower walls united by end walls and by inclined flanges which converge toward the central part of the draft gear, a pair of intermediate friction blocks each having two heads of triangular cross-section, one of said heads of said intermediate friction blocks being adapted to fit between and coact with the opposite inclined flanges of said casings, central friction blocks having diverging flanges adapted to coact with the other heads of said intermediate friction blocks, and springs mounted between said central friction blocks and said end walls of said casing.
5. The combination in a draft gear, of oppositely disposed casings having upper and lower walls united by end walls and by inclined flanges which converge toward the central part of the draft gear, a pair of intermediate friction blocks each having two heads of triangular cross section, one of said heads of said intermediate friction blocks being adapted to fit between and coact with the opposite inclined flanges of said casings, central friction blocks having diverging flanges adapted to coact with the other heads of said intermediate friction blocks, and springs mounted between said central friction blocks and said end walls of said casing,
- said intermediate friction blocks and said central friction blocks being supported and retained in position by the upper and lower walls of said casings.
6. The combination in a draft gear of a yoke, a pair of casings mounted within said yoke, said casings being provided with friction surfaces, a pair of side friction blocks each engaging the friction surfaces of said casings, and compressible mechanism extending in opposite directions from the inner parts of said side friction blocks to each of said casings, the coacting surfaces of said side friction blocks and said casings being adapted to cause the separation of said blocks upon movement of said casings toward each other.
7. The combination in a draft gear of a yoke, a pair of casings mounted in said yoke, said casings being provided with oppositely disposed inclined friction surfaces, side friction blocks each having inclined surfaces adapted to coact with the opposite inclined surfaces on said casings, said side friction blocks being provided with inwardly directed parts having other inclined surfaces formed thereon, central friction blocks having inclined surfaces adapted to coact with said other inclined surfaces of said side friction blocks, and compressible mechanism extending between said central friction blocks and said casings, said side friction blocks being adapted to move outwardly and said central friction blocks being adapted to separate longitudinally of the yoke upon compression of the draft gear.

In testimony whereof, I have subscribed my name.

ROY J. COOK.
